JAIL DOOR OPERATOR

Charles B. Bednar, Cleveland, Ohio, assignor to Van Dorn Company, a corporation of Ohio.
Continuation of application Ser. No. 800,277, Mar. 18, 1959. This application Dec. 29, 1965, Ser. No. 518,522
14 Claims. (Cl. 49—17)

This application is a continuation application of my prior application S.N. 800,277, filed March 18, 1959, now abandoned.

This invention pertains to the art of door operators and more particularly to a door operating and locking mechanism which may be remotely or locally actuated.

The invention is particularly applicable to the art of jail doors and will be described with particular reference thereto, although it will be appreciated that the invention has broader and other applications.

In the art of jails, it is known to provide a plurality of jail doors with electric power operating mechanism whereby the doors may be selectively or as a group unlocked, opened, closed and locked from a remote position.

With such an arrangement and with mechanism immediately adjacent to the door which is capable of unlocking and opening the door, it is necessary that the entire mechanism be securely sealed in a housing to prevent any tampering by the prisoners. On the other hand, it is also necessary to provide for manual operation of the doors by the jail guards in case of an electric power failure or by the prisoners themselves in case of a power failure coupled with an emergency calling for immediate evacuation of all of the jail cells.

The necessity to enclose the mechanism in a securely sealed housing has created a problem with maintenance, particularly of lubrication of the moving parts of the mechanism over a long period of years.

Another problem with jail doors operating and locking mechanism has been the cost and the unduly complicated mechanisms required in order to provide the required manual and remote operation.

Still another problem with jail door operating mechanism has been the habit of the prisoners to attempt to stop or interfere with the power operated closing of a door. In many instances this has resulted in an overload of the actuating motor resulting in its burning out with the consequent maintenance problems. Still further in connection with this problem has been the tendency on the part of the prisoners to attempt to interfere with any exposed portions of the locking mechanism.

The present invention deals with all of these problems. It provides a door operating and locking mechanism which is much cheaper to build than anything heretofore known, is simple and positive in operation and which requires a minimum or no maintenance through the years.

Thus in accordance with the present invention, a door operating mechanism is provided including a motor and a power drive mechanism operable under the force of the motor to open and close the door, the power drive mechanism being of the one way or self locking type, that is, of the type which will transmit motion or force in one direction only, namely, from the motor to the door whereby the power operating mechanism acts as one of the locks for the door in any position, either part way open or all the way closed, in combination with means to release the locking effect of the self-locking mechanism.

Further, in accordance with the present invention, the power drive mechanism includes an overload clutch

2

set to slip or release at torques below the maximum rating of the motor.

Still further in accordance with the invention is a jail door operating and locking mechanism wherein the rack moves the door through a spring and latch arrangement so arranged that as the door is manually closed, the latch releases the spring to complete the locking operation.

Also in accordance with the invention, a power operated jail door operating mechanism is provided which serves to lock the door in any position to which the power mechanism has moved the door in combination with other mechanical locking means, provision being made for either remotely disengaging the locking effect of the operating mechanism or of the mechanical locking means whereby the doors may be manually operated by the jail guards or by the prisoners respectively.

Further in accordance with the invention, a permanent self-lubricated rack gear is provided wherein the teeth of the rack face upwardly and members extend along the sides of the rack above and below the end and roots of the teeth respectively and are arranged with the rack to provide an open-topped liquid-tight container to be at least in part filled with lubricating oil.

Accordingly, the principal object of the invention is to provide a novel and improved door operating and locking mechanism.

It is also an object of this invention to provide such a mechanism which is of simplified and inexpensive construction, while at the same time being highly effective for its intended purpose.

Another object of this invention is to provide a novel door operating mechanism which may be converted readily from power operation to manual operation, or vice versa, and still remain effectively tamperproof.

Another object of this invention is to provide a novel motor-driven door operating and locking mechanism in which the motor drive constitutes a novel and simplified auxiliary lock which prevents the door from being opened by a prisoner.

Another object of this invention is to provide a novel motor-driven door operating mechanism which has provision for preventing the motor from being burned out if a prisoner jams the door.

Another object of this invention is to provide a novel door operating mechanism which includes a motor drive for normally operating the door and which has novel provision for selectively disconnecting the motor drive from the door.

Another object of this invention is to provide a novel door operating mechanism which includes a motor drive for normally operating the door and which has novel provision for releasing the motor drive and for unlocking the door simultaneously manually.

Another object of this invention is to provide a novel door operating mechanism which includes a motor drive for normally operating the door and which has novel provision for releasing the motor drive and for conditioning the door to be opened individually by a key which operates a lock on the door that is inaccessible to the prisoner, so as to be tamperproof.

A further object of this invention is to provide a novel motor-driven door-operating mechanism which is self-lubricating.

The invention may take physical form in certain parts and arrangements of parts, the preferred embodiment of which will be described in detail in this specification and illustrated in the accompanying drawings which form a part hereof and wherein:

FIGURE 1 is a front elevational view, with parts broken away for clarity, of a door operating and locking mecha-

3

nism illustrating a preferred embodiment of the present invention;

FIGURE 2 is a vertical section taken approximately along the line 2—2 in FIGURE 1;

FIGURE 3 is a vertical section taken approximately along the line 3—3 in FIGURE 1;

FIGURE 4 is a right end elevational view of the FIGURE 1 apparatus;

FIGURES 5, 6 and 7 are enlarged fragmentary elevational views showing the actuation of the operating means for the two mechanical locks for the door as the door is closed and locked, the successive figures showing the successive stages of this operation;

FIGURE 8 is a fragmentary sectional view taken approximately along the line 8—8 in FIGURE 1;

FIGURE 9 is a view taken approximately along the line 9—9 in FIGURE 1; and

FIGURE 10 is an enlarged fragmentary front elevational view showing the position of the parts when the worm drive is disengaged from the rack.

Referring now to the drawings wherein the showings are for the purposes of illustrating a preferred embodiment of the invention only and not for purposes of limiting same, FIGURE 1 shows a conventional jail door 20 composed of spaced horizontal and vertical bars which are interconnected to form a rigid unit. The door is slidably mounted on a doorway frame which includes a top rail 21 disposed just above the top of the door and a depending vertical right side member 22 toward which the door is to be moved when being closed.

The door is suspended from a door carriage 23 which has a pair of spaced grooved rollers 24 and 25 riding along an upwardly facing rounded track 26 carried by the top rail 21 of the doorway frame, as best seen in FIGURE 2. As shown in FIGURE 2, the door carriage 23 is of inverted L-shape, presenting an upper horizontal leg 23a which extends rearwardly in FIGURE 1. At its front side the door carriage 23 is bolted to an L-shaped member 27 which is connected to the top of the door 20. With this arrangement the door 20 is adapted to move as a unit with the door carriage 23 as the latter moves lengthwise along the doorway frame rail 21.

An elongated horizontal rack 28 having teeth along its top extends through and is fastened to a U-shaped channel member 36 which is slidably mounted on top of the horizontal top leg 23a of the door carriage 23. This channel member 36 extends about two-thirds of the length of the rack 28, terminating at each end short of the corresponding end of the rack, as shown in FIGURE 1.

The rack 28 carries a cam 29 on its right end which cooperates with a latch 30 pivotally mounted at 31 on the door carriage to move in unison therewith during the power operation of the door.

As best seen in FIGURE 3, the cam 29 has a rearwardly projecting horizontal leg 29a which is rigidly connected to the rack 28 through spacer blocks 32 and 33 and a bolt 34 which interconnects them. The uppermost spacer block 33 has a reduced upper end which is slidably received in an elongated slot 35 formed in leg 23a.

Referring to FIGURE 1, the bottom leg 29a of the cam terminates short of the right end of the upstanding cam proper 29 and presents a vertical shoulder 29b which faces to the right. The pivoted latch 30 presents a depending lip 30a which is adapted to engage this shoulder 29b and thereby couple the door carriage 23 to the cam 29 and the rack 28 when the door is being closed.

The latch 30 presents an inclined bottom face 30b which is positioned to engage the rearwardly extending horizontal bottom leg 40a of an L-shaped member 40 (FIGURE 3) which is bolted to an inverted U-shaped bracket 41 attached to the doorway frame. As described in detail hereinafter, while the door 20 is being moved from an open position to a closed position (from left to right in FIGURE 1), the lip 30a on the latch continuously

4

engages the shoulder 29b on the cam. Thus, at this time the rack 28 is coupled to the door carriage 23 to move therewith. When the door 20 reaches its closed position, the inclined bottom face 30b on the latch 30 engages the left end of the bottom leg 40a of the L-shaped member 40 carried by the doorway frame. The latch 30 pivots counterclockwise in FIGURE 1, moving its lip 30a up out of engagement with the cam shoulder 29b and thereby uncoupling the door carriage 23 and the rack 28. This leaves the rack 28 free to continue moving further to the right in FIGURE 1, for a purpose which will be described in detail hereinafter.

In accordance with the present invention, there is provided a spring coupling between the rack 28 and the door carriage 23 which biases the rack to the right relative to the carriage 23 when cam 30 is raised as just described.

Thus as shown in FIGURE 1, the horizontal top leg 23a of the door carriage 23 is formed with an elongated slot 150 which slidably receives a slide block 151 bolted to the underside of the rack 28. An inverted L-shaped connector 152 is attached to the threaded end of a horizontal rod 153 by means of lock nuts 154 and 155. A bracket 156 is welded onto the back of the door carriage 23 below the latter's top leg 23a. This bracket presents rearwardly extending opposite end walls 157 and 158 which slidably receive the rod 153 connected to the rack. A metal washer 159 is retained on the rod 153 by means of a retainer 160. A coil spring 161 is engaged under compression between this washer and the left end wall 157 on the bracket 156 on the door carriage. This spring biases the slide block 151 to the left end of the slot 150 in the door carriage.

In the normal operation of the door, the rack 28 is driven to the right in FIGURE 1 to close the door by means of a drive imparted to the rack by a gear motor unit. As shown in FIGURE 1, this unit includes an electric motor 50 mounted on a base 51 which is pivotally supported at 52 adjacent its left end on a fixed support 53.

Referring to FIGURE 9, the motor has a rotary output shaft 54 which is coupled to a worm 55 through overload clutch 130 constituted by a first clutch plate 131 attached to the motor shaft 54 and a confronting second clutch plate 132 coupled to the worm shaft 133. A coil spring 134 adjusted by a nut 135 biases the second clutch plate 132 resiliently against the first clutch plate 131. For torque loads below that which the clutch is set to transmit, i.e., the maximum designed output torque of the motor 50, the clutch 130 couples the motor shaft 54 to the worm shaft 133. The worm 55 meshes with a small worm gear 56 which is connected to a larger spur gear 57. The latter meshes with the teeth formed on the top of the rack 28. For torque loads in excess of the motor designed output torque, the clutch slips.

As shown in FIGURES 1 and 9, the worm 55 and the gears 56 and 57 are rotatably supported by a housing 59 which is connected to the motor housing. The gears 56 and 57 are mounted rotatably on a shaft 60 which is fixedly mounted in the housing 59 extending horizontally from front to back thereon and perpendicular to the axis of the worm 55. A coil spring 61, which loosely encircles the shaft 60, is under compression between the front wall 59a of this housing and the worm gear 56. This spring positions the worm gear 56 in meshing engagement with the motor driven worm 55 and positions the spur gear 57 in meshing engagement with rack 28. This arrangement constitutes a right angle worm drive for driving the rack 28 from the motor 50. The gear mechanism is a one way or self-locking mechanism which transmits motion or power in one direction only, namely, from the motor to the door.

An important and advantageous characteristic of this drive arrangement for the rack is that it constitutes an auxiliary lock for the door. The friction between the teeth on the worm 55 and the gear 56 and the pitch or

angle of the teeth is such as to be self locking against transmitting motion from the gear 56 to the worm 55. Thus any amount of force exerted on the door to the left cannot force the rack 28 to the left against the restraining force exerted by these meshing parts. Accordingly, as long as the gear motor unit is in the position shown in FIGURE 1, with the spur gear 57 meshing with the rack 28, the door can be moved *only* by energizing the motor 50.

Also, the provision of the clutch 130 insures against burning out the motor 50 in the event that a prisoner jams the door against movement. In such event, the load on the motor will exceed the value for which the clutch is set and the first clutch plate 131 will simply overrun the second clutch plate 132 as long as the door is so restrained.

Since substantially the entire weight of the motor 50, housing 59, shaft 54, clutch 130, shaft 133, worm 55 and gears 56 and 57 is to the right of the pivotal support 52, this entire gearmotor unit tends to pivot clockwise in FIGURE 1 to maintain the spur gear 57 in meshing engagement with the rack 28. This is the normal condition of the mechanism. However, when it is desired to disconnect the gearmotor unit from the rack, this can be done by pivoting the gearmotor unit counterclockwise in FIGURE 1, as will be described in detail hereinafter.

The previously described U-shaped member 36 is sealed at its ends, as by welding, to the rack 28 and provides a reservoir for lubricant. As shown in FIGURES 1 and 4, the upstanding sides of this U-shaped member 36 extend above the rack and close the opposite ends of the recesses between successive teeth on the rack. Also the gear 57 is slightly narrower than the rack 28. Accordingly, these closed-off recesses constitute a reservoir for retaining a suitable lubricant. During each operation of the door, whether to open it or close it, these lubricant-filled recesses on the rack are engaged by the gear 57. The gear 57 picks up oil and carries it into the gear reduction housing to also lubricate the gears 55 and 56. The mechanism is permanently self-lubricated and requires no servicing. The length of the U-shaped member 36 along the rack may be varied as desired, as long as enough lubricant recesses are provided to make the mechanism substantially permanently self-lubricated.

In accordance with the present invention, the previously mentioned cam 29, which is carried by the rack 28, is arranged to operate two separate mechanical door locks. Referring to FIGURES 1 and 5-8, the upstanding portion of this cam presents a rise surface 60 which inclines upward from the right end of the cam, a horizontal top surface 61 which extends to the left from the upper end of the rise surface 60, and a fall surface 62 which extends downward to the left from the left end of the top surface 61.

A roller 63 is positioned to ride in succession over the rise surface 60, the top surface 61 and the fall surface 62 on the cam as the cam and the rack 28 move to the right in these figures. This roller is carried on one end of an arm 64 which at its opposite end is attached to a sleeve 65 (FIGURE 8) connected to a shaft 66 by means of a tapered pin 67 (FIGURE 3). As best seen in FIGURES 3 and 8, shaft 66 is rotatably mounted in the spaced opposite sides of the support bracket 41 mounted on the doorway frame. With this arrangement, as the cam 29 and the rack 28 move to the right in FIGURE 1, the rise surface 60 on the cam forces the arm 64 counterclockwise in FIGURE 5 to turn the shaft 66 a corresponding amount. The roller 63 and the arm 64 are held in their uppermost position as the horizontal top surface 61 on the cam moves beneath the roller. This condition is shown in FIGURE 6. Then, as the rack and cam continue to move to the right, the roller 63 rides down along the fall surface 62 on the cam and the arm 64 and shaft 66 move clockwise to their previous positions. This condition is shown in FIGURE 7.

Shaft 66 is connected to one end of a second arm 68 so that this arm moves angularly in unison with the shaft. As shown in FIGURES 3 and 8, the left end of the arm 68 is attached to a sleeve 69 which is secured to shaft 66 by a tapered pin 70. The right end of the arm 68 is pivotally connected at 71 to the upper end of a vertically reciprocative drop bolt 72. This drop bolt is slidably received by a guide 73 which is attached to the bracket 41 and guides the drop bolt for movement vertically. At its lower end the drop bolt is coupled to a vertically reciprocative rod 74. This rod at its lower end is connected to a vertically reciprocative latch member 75 which cooperates with a keeper 76 attached to the right end of the door 20. The keeper presents an upwardly-facing notch 77 which is positioned to receive the latch member 75 when the door is fully closed. This constitutes one lock for the door. It will be noted that this lock is exposed to tampering, e.g., filling the notch 77, but in accordance with the present invention two additional locks are provided so that such tampering cannot enable the door to be opened by unauthorized persons.

Attention is now directed to the coupling between the drop bolt 72 and the bar 74 which is connected to the latch member 75. As best seen in FIGURE 4, the drop bolt 72 is formed with a horizontal extension 72a at its lower end which has an oversized hole 78 which slidably receives the upper end of the bar 74. The bar 74 on its upper end carries a nut 79 which overlies the horizontal extension 72a on the drop bolt. With this arrangement, when the drop bolt is pulled upward it pulls the bar 74 and latch member 75 upward. However, the converse is not true. That is, when the latch 75 and bar 74 are pushed upward (or held upward) this does not impart an upward force to the drop bolt 72. Accordingly, if a prisoner in some manner is able to lift up on the bar 74, or if he stuffs the notch 77 in the keeper 76 so that the bar 74 cannot drop down, this will have no effect on the position of the drop bolt 72. Thus, it is not possible for the prisoner to impart an upward movement to the free end of the arm 68.

The importance of this safety feature will be apparent now. A vertically reciprocative lock bar 80 has its upper end pivotally connected at 81 to the arm 68 between the latter's pivoted and free ends. A guide 82 bolted to the bracket 41 guides the lower end of this lock bar for slidable movement vertically. Toward its upper end the lock bar 80 carries a forwardly projecting block 83 (FIGURES 3 and 8) which is shaped and dimensioned to be received in a rectangular notch 84 formed in the horizontal top rail 23a of the door carriage 23. The notch 84 is positioned to receive the block 83 on lock bar 80 when the door has closed fully and the arm following roller 63 just begins to ride off the left end of the top surface 51 on the cam. In this position of the parts, the fall surface 62 on the cam is engaged by the cam follower roller 63 and the arms 64 and 68 begin to drop down. At this time, the lock bar 80 constitutes a second lock which acts between the frame and the door carriage 23. This second lock can be released only by lifting up on the arm 68 and, as already pointed out, it is not possible to lift this arm up merely by tampering with the first lock formed by latch member 75 and the keeper 76 on the door.

A door stop is provided in the form of a block 90 which is carried by the frame bracket 41 and is positioned in the path of movement of a shoulder 91 presented by the door carriage 23.

Power operation of the door

In the operation of this mechanism, starting with the door in a partly or fully open position (to the left in FIGURE 1) the motor 50 is energized to drive the rack 28 to the right. At this time the rack is coupled to the door carriage 23 through the described coupling between the latch 30 carried by the door carriage and the

cam 29 carried by the rack. Therefore, the door carriage 23 and the door 20 move to the right in unison with the rack.

At this time the slide block 151 attached to the rack 28 is at the left end of the slot 150 in the door carriage and the spring 161 is tightly compressed.

When the door, door carriage and rack have moved to the position shown in FIGURE 5, the rise surface 60 on the cam 29 carried by the rack begins to move past the roller 63. As the roller rides up across this rise surface on the cam, the right end of arm 64 moves upward, causing shaft 66 to turn counter-clockwise and thereby causing the other arm 68 to move upward. The upward movement of arm 68 pulls the drop bolt 72 and latch bar 74 upward, as well as pulling the lock bar 80 upward a sufficient amount that the block 83 will be spaced slightly above the top 23a of the door carriage as the latter advances to the right.

Upon continued movement of the rack and the door carriage to the right, the top 23a of the door carriage passes beneath the block 83 on lock bar 80 and the top face 61 of cam 29 passes beneath the roller 63, maintaining both arms 64 and 68 lifted. This condition is shown in FIGURE 6.

As the left end of the horizontal top surface 61 on the cam reaches the roller 63, the inclined bottom face 30b on the pivoted latch mounted on the door carriage engages the L-shaped member 40 mounted on the doorway frame. As a consequence, latch 30 is pivoted counter-clockwise in FIGURE 1, disengaging from the cam 29 carried by the rack 28. At this time, the shoulder 91 on the door carriage engages the stop 90, which prevents any further movement of the door carriage and the door to the right. At this time the door is fully closed, but not locked.

Due to its release by the pivoted latch 30, the rack is free to continue to move to the right, and the fall surface 62 on cam 29 passes beneath the roller 63. Also spring 161 expands. As the roller rides down along this fall surface the right ends of the arms 64 and 68 move downward, lowering the drop bar 80 until the block 83 on the latter seats in the notch 84 formed in the top 23a of the door carriage. The latch member 75 drops into the notch 77 in the keeper 76 on the door at the same time. Thus, the door and the door carriage are locked in three places.

Thus, the overtravel movement of the rack 28, which takes place just after the door 20 has been closed, causes the door to be locked in two places.

In such overtravel movement of the rack 28, guide blocks 151, 33 engage against the right ends of the slots 150 and 35 in the door carriage 23.

The door may be unlocked and opened by this same power drive, simply by energizing the motor 50 in reverse. When this is done, the rack 28 is drawn to the left compressing spring 161. At the same time the surface 62 on the cam 29 raises arm 64 which in turn lifts drop bolt 72 and lock bar 80 to release these two mechanical locks. The door 20 is then free to move to the left on the carriage 23.

As the door commences to open cam 46a releases latch 30 and the rack is then locked to the carriage with spring 161 compressed. The door may continue to open until a limit switch (not shown) de-energizes the motor. The door is then locked open making it impossible for a prisoner to lock a guard in the cell.

If at any time while the door is being opened it appears that the prisoner or prisoners will attempt to break out, the motor is simply de-energized at which time the door stops moving, and because of the self-locking, one-way power drive mechanism between the rack and the motor 50, the door will be locked in that position and cannot be further opened except upon re-energization of the motor as previously described.

Suitable limit switches (not shown) are provided for automatically de-energizing the motor 50 when the door comes to the fully-opened or fully-closed position. The use of such limit switches and the electrical circuits associated therewith form no part of the present invention. Obviously, limit switches may also be provided for indicating on pilot lights or the like, when a door is in the fully-locked or open position.

Also, if a prisoner should jam the door while the motor is on, the clutch 130 will prevent the resulting overload from burning out the motor.

Manual operation of the door

In accordance with the present invention, there is provided a novel arrangement for selectively disconnecting the power drive, either for a single door or for several doors at the same time. This is done when it is desired to operate the door manually.

Referring to FIGURE 1, the housing 59 in the gearmotor unit carries a horizontal rod 92a which constitutes a cam follower riding in a cam slot 92b formed in a horizontally reciprocative cam plate 92. The cam plate 92 is suspended from a pair of brackets 93, 94 attached to a horizontally reciprocative shaft 95.

The cam slot 92b presents a downwardly offset seat 92c in which the follower 92a rests when the gearmotor unit is in its normal position, meshing with the rack 28. To the left of its seat 92c the cam slot presents an upwardly inclined face 92d which leads to an elongated horizontal upper seat 92e, which is disposed at a higher level than the seat 92c. When the cam plate 92 is moved to the right in FIGURE 1, the cam follower 92a rides up the incline 92d and engages the upper seat 92e. When this action takes place, the housing 59 of the gearmotor unit is thereby lifted up away from the rack 28 so that it is no longer in meshing engagement with the rack.

The shaft 95 to which cam plate 92 is connected is slidably supported by a plurality of fixedly positioned bearings 96. A suitable mechanical operating mechanism (not shown) is provided for operating shaft 95. Such operating mechanism is accessible only to authorized personnel, such as prison guards. A single shaft 95 is provided for several doors, each of which has its own individual gearmotor unit and its own locking mechanism, as described.

In accordance with the present invention, the shaft 95 may be positioned in one of three different positions.

In the first position, shown in FIGURE 1 and described already, it permits each gearmotor unit to mesh with the rack for the corresponding door, so that each door is under the control of the respective gearmotor unit.

In a second position of the shaft 95, all of the gearmotor units are disconnected from the respective doors, but the mechanical locks remain locked. Each door may be opened individually only by a key possessed by authorized prison personnel.

The entire mechanism is covered or concealed from access from the jail corridor by a continuous cover plate 102, a fragmentary part of which is shown in phantom in FIGURE 1 and in cross-section in FIGURE 3.

As shown in FIGURE 3, a plate 100 formed with an oblong keyhole 101 is connected to the shaft 95 to move in unison therewith. When the shaft is moved to the right, the keyhole 101 comes into registration with the shaft 66 and an opening 103 in the cover plate 102 (see FIGURE 3) when the cam follower 92a engages the upper seat 92e in the cam slot 92b just slightly beyond the inclined portion 92d of the cam slot. Shaft 66 carries a cross pin 66a, which projects above and below shaft 66 when the locks are engaged, as shown in FIGURE 1. This cross pin 66a may be engaged by a suitable key (not shown) which is inserted through the keyhole 101 when the latter registers with the shaft 66. By turning this key, the shaft 66 may be turned to lift the drop bolt 72 for the first lock and the lock bar 80 in the second

lock, thereby opening both locks. The gearmotor unit having been moved up out of engagement by the cam plate 92, the door is unlocked now and may be opened.

After being opened in this manner, the door may be moved back and forth freely. When the door is opened, the door carriage 23 is moved to the left. Through the coupling provided by spring 161 and slide block 151, the door carriage will retract the rack 28 to the left, even though the latch 30 remains uncoupled from cam 29. If the door is again closed manually, the spring 161 will insure that the rack 28 will operate both mechanical locks 75 and 80 automatically.

Manually, as is used in this specification and in the claims, is used to connote the direct application of force to the door itself to open and close it as distinguished from the application of manual force to an operating mechanism such as a crank or a push rod or the like.

In a third position of the shaft 95, all of the gearmotor units operated by that shaft are disconnected from the respective doors and all of the locks on the several doors are automatically unlocked.

This third position of the shaft 95 is farther to the right in FIGURE 1, with the cam follower 92a engaging the upper seat 92c in the cam slot 92b near the left end of the latter, as shown in FIGURE 10.

The mechanism for releasing the door locks in this position of shaft 95 includes a chain 110 (FIGURE 1) pivotally connected at its lower end to the upper arm 68 in the lock-operating mechanism and pivotally connected at its upper end to a slide member 111 which is slidably mounted on shaft 95. This chain 110 is a flexible tension member and in effect serves as a lost motion mechanism permitting the transfer of force in one direction only, namely, from the shaft 95 to the lock-operating mechanism and allowing the lock-operating mechanism to be otherwise operated without such chain 110 transmitting the motion of lock operation to the shaft 95. A stop member 112 is rigidly mounted on shaft 95 to move in unison therewith. When shaft 95 is pulled far enough to the right in FIGURE 1, this stop member 112 engages the slide member 111, and upon continued movement of shaft 95 to the right, it pulls the slide member 111 to the right also. This pulls the chain 110 up around a fixed bearing provided by a tubular horizontal member 113, lifting the free end of arm 68 upward. Such upward movement of arm 68 releases the latch member 75 at the first lock and also releases the lock bar 80 at the second lock.

This action takes place at every one of the doors so that such movement of the shaft 95 is effective to open the locks at all of the doors simultaneously.

Each door may be opened manually now and may be moved back and forth freely. The spring 161 and slide block 151 couple the door carriage to the rack at this time so that the rack will slide back and forth with the door carriage even though latch 30 is uncoupled from cam 29.

When the shaft 95 is returned to the position shown in FIGURE 1, another stop member 114 on this shaft engages the slide 111 and moves it to its position shown in FIGURE 1. The weight of the mechanism connected to the lower end of chain 110 returns the parts of the two locks to the FIGURE 1 position.

The weight of the pivotally mounted gearmotor unit will cause it to drop down into engagement with the rack when such return movement of the shaft 95 takes place. When such return movement takes place, the follower 92a attached to the gearmotor unit rides down into the recesses 92c in the cam slot on cam 92.

As a precaution to insure that the motor drive is locked in meshing engagement with the rack, there is provided an actuator 140 slidably mounted on shaft 95. This actuator is engaged between two compression springs 141 and 142 which normally position it midway between the brackets 93 and 94. Actuator 140 extends down from shaft 95 over a projection 143 on the housing 59 of the

worm drive when the shaft is returned and thus prevents a force on the rack 28 from raising the gearmotor unit. If the teeth of the drive unit do not immediately mesh with the rack, the side of actuator 140 strikes the side of projection 143 and the actuator 140 slides on shaft 95 compressing one of the springs 141 or 142. As soon as the door is moved manually, or as soon as the motor is started, the gears mesh and actuator 140 is moved to the position shown in FIGURE 1.

From the foregoing description, it will be apparent that the illustrated embodiment constitutes a simplified and practical arrangement for the accomplishment of the stated purposes of this invention. However, it is to be understood that while there has been described in detail herein, and illustrated in the accompanying drawings, a presently preferred embodiment of the present invention, various modifications, omissions and refinements which depart from the disclosed embodiment may be adopted without departing from the spirit and scope of this invention.

Having thus described my invention, I claim:

1. In combination with a door which is movable between open and closed positions, a doorway frame at which said door is mounted, and a first lock mechanism for locking said door closed, said first lock mechanism including a drop bolt which is movable downward to lock the door closed, a second lock mechanism for locking the door closed which is positioned to be inaccessible from behind said door, common operating means which is actuated when the door is closed to operate both lock mechanisms to lock the door in a closed position, and means coupling said common operating means to said drop bolt for downward movement of said drop bolt when said common operating means is actuated but ineffective to prevent said actuation of said common operating means if said drop bolt is held upwardly out of locking relationship with said door, said coupling means including a link which is movable downwardly in response to actuation of said common operating means, said link having a portion which defines an upwardly facing shoulder and having an opening in said portion, and said drop bolt having means at its upper end which extends slidably up through said opening and which has an enlarged portion resting on the top of said shoulder.

2. In combination with a door frame having a top portion and a side portion extending down from said top portion, a door carriage slidably mounted on said top portion, a door disposed below said top portion of the doorway frame and connected to said carriage to be moved slidably thereby between an open position in which the door is positioned away from said side portion of the doorway frame and a closed portion in which the door is positioned next to said side portion of the frame, and a first lock mechanism acting between the door and said side portion of the door frame for locking the door closed, the improvement comprising: a second lock mechanism disposed above said top portion of the door frame and inaccessible from behind said door, said second lock mechanism including a latch engageable with an apertured member rigidly fastened to said door carriage to lock the door closed, a cam which is above said top portion of the door frame upon closing of the door, a cam follower which engages said cam and is displaced thereby upon said movement of the cam, and means actuated by said cam follower for operating both said lock mechanisms to lock the door when the door is closed, said last-mentioned means operating said second lock mechanism to lock the door closed independent of the operation of said first lock mechanism, a power-driven rack mounted slidably above said top portion of the doorway frame, and coupling means which couples the rack to the door carriage during movement of the door from open to closed positions and release means for uncoupling the rack from the door carriage upon continued movement of the rack after the door has reached its closed position, said cam being connected to said rack to move therewith for operating

said first and second lock mechanisms in response to said continued movement of the rack after the door is closed.

3. The combination as defined in claim 2 including a motor and a self-locking gear drive which is driven by said motor and meshes with said rack to operate said rack, said drive effectively locking the rack and the door against movement except by said motor and thereby constituting a third lock for said door.

4. In combination with a door which is movable between open and closed positions, a doorway frame at 10 which said door is mounted, said doorway frame having a side portion toward which the door is moved when being closed and a top portion disposed above the top of said door when said door is closed, a first lock means acting between said door and said side portion of said doorway for locking said door closed, a second lock mechanism disposed above said top portion of said doorway frame and inaccessible from behind said door, said second lock mechanism being operative to lock the door closed, the improvement comprising: a door carriage operably connected to said door, a cam means carried by said carriage, a link for unlocking said lock mechanisms in unison, said second lock mechanism adapted to engage said carriage to lock said door, and lost motion means between said link and said first lock mechanism whereby locking movement of said second lock mechanism is not prevented by blocking locking movement of said first mechanism, and a shaft mounted to be reciprocated in two directions above said top portion and generally parallel to said carriage, and means on said shaft for pulling said link upwardly when said shaft is moved in one direction only beyond a predetermined position.

5. In a door operating mechanism having a rack which is movable lengthwise to open or close said door, a motor, and gear means driven by said motor and meshing with said rack to drive the latter, said gear means being one-way, self-locking for locking the rack and door against movement except through drive imparted to said gear means by said motor, the improvement comprising: an actuator means for selectively moving said gear means out of engagement with said rack, said actuator means comprising a member capable of being manually moved adjacent said gear means and conversion means for converting movement of said member into selective movement of said gear means away from said rack, said member being a shaft capable of being reciprocated adjacent said gear means.

6. The improvement as defined in claim 5 wherein said gear means and said motor are mounted as a unit, said unit being pivotally mounted on an axis transverse to said door and spaced horizontally from said gear means, said conversion means including a cam and cam follower operably connecting said shaft and said unit whereby movement of said shaft pivots said unit away from said rack.

7. A jail door operating mechanism comprising: a reciprocally mounted rack, said door being carried by said rack, an electric motor pivotally mounted adjacent said rack and having a pinion drive gear adapted to engage said rack, a lock mechanism for locking said door in a closed position, a cam means carried by said rack for actuating said lock mechanism when said door is closed, a shaft shiftable in a first and second axial direction parallel with said rack, means on said shaft for pivoting said motor when said shaft is shifted in said first axial direction to release said gears, and a lock actuator on said shaft for unlocking said lock mechanism when said shaft is shifted in said first axial direction, a means on said shaft for pivoting said motor when said shaft is shifted in said second direction to release said gear and means for preventing actuation of said actuator when said shaft is shifted in said second axial direction.

8. A remotely controllable operating mechanism for moving a jail door from an opened to a closed position and releasably locking said door in either of said positions

or any intermediate position comprising in combination: a first gear locked to and movable with said door, a gear motor arrangement comprised of an electric motor and a second gear operatively associated with said electric motor through a wormgear drive arrangement capable of transmitting torque only from said motor to said second gear, means mounting at least said second gear for vertical movement, said second gear being urged downwardly by the force of gravity into driving engagement with said first gear, whereby when said motor is not electrically energized, said door will be locked against movement in either direction, said gear motor arrangement being movable to move said second gear from engagement with said first gear, and manually operable means for raising said second gear out of engagement with said first gear whereby said door may be freely moved in either direction.

9. A remotely controllable operating mechanism for moving a jail door as defined in claim 8 including a first hold down element secured onto said motor arrangement, a second hold down element, and means for shifting said second hold down element into blocking relationship with said first hold down element when said second gear is in said driving engagement with said first gear.

10. A jail door operating and locking arrangement comprising in combination a door frame defining an opening, a housing associated with said frame and extending to a point substantially remote from and inaccessible from the immediate vicinity of said frame, a door movable to open and close said opening, a first gear positioned within said housing above said door and having means operatively associating same with said door whereby movement of said first gear moves said door, a second gear in said housing above said door and normally meshing with said first gear, an electric motor in said housing above said door operatively associated with said second gear and adapted, when appropriately electrically energized, to rotate said second gear in either of two directions to open and close said door, means locking said second gear from rotation when said electric motor is not energized whereby said door, when said electric motor is not energized, is locked against movement in either direction, means supporting said second gear for movement into and out of mesh with said first gear, a rod-like member positioned in said housing and extending generally from said electric motor to said substantially remote point, means urging said second gear into mesh with said first gear at all times except when said rod-like member moves said gears out of mesh whereby said door is unlocked and can be freely moved independently of any other door operating mechanism.

11. A jail door operating and locking arrangement comprising, in combination, a door frame defining an opening, a housing associated with said frame and extending to a point substantially remote from and inaccessible from the immediate vicinity of said door frame; a door movable to open and close said opening; a first gear positioned within said housing and generally above said door; means for securing said door onto said first gear; an electric motor with an output shaft mounted within said frame and generally above said door; a drive train between said shaft and said first gear whereby rotation of said shaft in one direction opens said door and rotation of said shaft in the opposite direction closes said door; locking means in said drive train for allowing torque transmission through said train in only the direction from said motor to said first gear during normal operation of said door; a manually movable rod-like element extending from the vicinity of said drive train to said remote, inaccessible point; and means for unlocking said locking means of said drive train upon movement of said rod-like element into a first position, a locking mechanism for locking said door in the closed position, and means for unlocking said locking mechanism upon movement of said rod-like element into a second position.

13

12. A jail door operating and locking arrangement as defined in claim 11 wherein said gear train includes a torque limiting clutching device.

13. A remotely controllable operating mechanism for moving a jail door from an open to a closed position and for releasably locking said door in either of said positions or in any intermediate position comprising, in combination, a housing above said door and having a remotely accessible opening; a first gear releasably locked to and movable with said door; a gear motor arrangement in said housing above said door and comprising an electric motor, a second gear, and a drive connection between said motor and said second gear; means for mounting said motor arrangement with said second gear meshing with said first gear; a remotely controlled mechanism including a manually movable member extending from said remotely accessible opening to the general vicinity of said motor arrangement; means responsive to movement of said member in a first position for allowing said motor to drive said first gear through said second gear, means for preventing said second gear from driving said motor when said movable member is in said first position; means responsive to movement of said member in a second position for releasing said first gear from said drive connection and, thus, said motor whereby said door may be manually moved between open and closed positions, a second locking mechanism independent of said motor arrangement and operative to lock said door closed, means for unlocking said first gear from said door when said door is closed, means responsive to movement of said first gear by said motor in the closing direction after said

door is closed electrically to lock said second locking mechanism, and means responsive to movement of said first gear by said motor in the opening direction to first unlock said second locking mechanism and then lock said first gear to said door for movement of said door with said first gear and in the opening direction.

14. A remotely controllable operating mechanism for moving a jail door as defined in claim 13 wherein said gear train includes a torque limiting clutching device.
